CLAIM

The ornamental design for a chair, as shown and de-
scribed.

DESCRIPTION

FIG. 1 is a front perspective view of the chair showing
my design;

FIG. 2 is a top plan view;

FIG. 3 is a side elevational view;

FIG. 4 is a front elevational view;

FIG. 5 is a top plan view; and

FIG. 6 is a sectional view taken along the line 6—6 of
FIG. 2 and looking in the direction of the arrows
thereof.

The side of the chair not shown is a mirror image of the
side shown in FIG. 3.
